(57) CLAIM

We claim the ornamental design for the stackable container, as shown and described.

DESCRIPTION

FIG. 1 is a top side perspective view of the new stackable container of the present invention;
FIG. 2 is a bottom side perspective view thereof;
FIG. 3 is a top plan view thereof;
FIG. 4 is a side elevational view thereof, the opposite side is a mirror image of FIG. 4;
FIG. 5 is an end view thereof, the opposite end is a mirror image of FIG. 5;
FIG. 6 is a top plan view thereof with the handle in a folded position;
FIG. 7 is a bottom plan view thereof; and,
FIG. 8 is a bottom side perspective view of an alternative embodiment thereof.
